DESIGN FOR A LIGHTING FIXTURE

Otto G. Hildebrand, Cleveland, Ohio, assignor of one-half to Fred W. Kramme, Cleveland, Ohio

Application March 21, 1933. Serial No. 47,538

Term of patent 7 years

To all whom it may concern:

Be it known that I, OTTO G. HILDEBRAND, a citizen of the United States, residing at Cleveland, in the county of Cuyahoga and State of Ohio, have invented a new, original, and ornamental Design for Lighting Fixture, of which the following is a specification, reference being had to the accompanying drawing, forming part thereof, wherein Fig. 1 is a side elevation and Fig. 2 is a fragmentary view with a part broken away.

My design consists essentially of a pair of vertically arranged scrolls connected together with an easy curve and a third overhanging scroll disposed at one side and at substantially the same height as the uppermost of the aforementioned pair of scrolls and supporting the lighting fixture.

I claim:

The ornamental design for a lighting fixture substantially as shown and described.

OTTO G. HILDEBRAND.
